UNITED STATES PATENT OFFICE

148,431

DESIGN FOR A COMBINED TRAY AND COMB HOLDER

Lola M. Lund, Burbank, Calif.

Application December 17, 1946, Serial No. 135,577

Term of patent 7 years

(Cl. D26—10)

To all whom it may concern:

Be it known that I, Lola M. Lund, a citizen of the United States, residing at Burbank, county of Los Angeles, State of California, have invented a new, original, and ornamental Design for a Combined Tray and Comb Holder, of which the following is a specification, reference being had to the accompanying drawing, forming a part thereof.

I claim:

The ornamental design for a combined tray and comb holder, as shown.

LOLA M. LUND.
